United States Patent Office.

GEORGE P. FULLER, OF PHILADELPHIA, PENNSYLVANIA.

Letters Patent No. 95,218, dated September 28, 1869.

IMPROVED CURTAIN-FIXTURE.

The Schedule referred to in these Letters Patent and making part of the same.

To all whom it may concern:

Be it known that I, GEORGE P. FULLER, of the city of Philadelphia, and State of Pennsylvania, have invented a new and improved Mode of Hanging Window-Shades in relation to ventilation; and I do hereby declare that the following is a full and exact description thereof, reference being had to the accompanying drawings, and to the letters of reference marked thereon.

The nature of my invention mainly consists in the arrangement of a pinion on one end of the roller on which the curtain is wound, and combining therewith a permanent rack, which is arranged on the window-facing, to preserve the height of the lower end of the curtain in the adjustment of the upper sash, the roller being supported by brackets, attached to the sash, and moving with the same, so that the pinion, by being turned around as it runs down the rack, winds the curtain around the roller, to leave an open space above the sash for the free passage of air, without altering the height of the lower end of the shade.

It further consists in the arrangement of a revolving shaft above said pinion, which has a pinion or small gear-wheel on one end, and a pulley on the other, which is also fast to the shaft, and which is provided with an endless cord, so that when the upper sash is in its most elevated position, the two pinions shall gear into each other, and, by the manipulation of the cord, said roller be turned either way, as may be required, to wind or unwind the curtain or shade, for the adjustment of its lower end.

It also consists in the arrangement of a gum roller on one or both of the brackets which sustain the shade-roller, so as to bear upon the window-jamb, as the sash is moved up and down to hold the same in any adjusted position.

The invention will be understood by the following description.

In the accompanying drawings—

Figure 1 is a front view of a window, in which the shade is hung on a roller, the journals of which have bearings in the brackets F F, that are secured to the upper sash C.

Figure 2 is a vertical section at the line a b of fig. 1.

Figure 3 is a perspective view of one of the brackets F, which is provided with a sash-sustaining gum roller, M.

Like letters in all the figures indicate the same parts.

A, figs. 1 and 2, is a window-frame.

B is the lower and C the upper sash.

D is the shade, which is hung on a roller, E, in the usual manner.

To provide for lowering the upper end of the curtain or shade D with the sash, so as to permit the air to pass freely over it, for the more perfect venti-

lation of the room, and to prevent strong currents flapping the shade, which is incidental to the usual mode of retaining the upper end in its elevated position, I attach brackets F to the upper part of the sash C, for the support of the journals a a of the said roller E.

And to preserve the requisite height to the lower end of the shade, there is a spur-wheel, G, on one end of the roller E, which gears into the permanent rack H, on the window-facing b.

The wheel G, being at its pitch-line of the same diameter as the roller, as the shade is wound around the latter, in the revolutions caused by the said wheel running down the rack H, the required height of the lower end of the shade is preserved, with but a slight variation, caused by increasing the size of the roll in the winding of the shade.

When the sash C is in its most elevated position, the wheel G is brought into gear with the pinion I, on one end of the short shaft J, and there being a sheave, K, on the other end of the shaft, the height of the lower end of the shade is adjusted by means of the endless cord L, which passes around the sheave and the pin c.

The brackets F are provided with rollers, M, seen more clearly in fig. 3.

The said rollers are constructed of vulcanized rubber, or similar material, and readily yield to any inequalities as the sash is moved up and down, and, by their friction and pressure upon the jamb b, sustain the sash in any adjusted position.

The sashes may be sustained and locked by attaching a flat spring provided with a friction-roller, to the lower end of the upper sash, so that the roller shall bear against the outside of the lower sash, in the movement up and down of the upper sash, and be sprung upon the upper edge of the lower sash when the former is brought into its most elevated position.

What I claim as my invention, and desire to secure by Letters Patent, is—

1. The combination and arrangement of the spur-wheel G, roller E, and rack H, with the sash C, for maintaining the proper height of the lower end of the shade, substantially as described.

2. The arrangement of the pinion I, sheave K, shaft J, and cord L, in relation to the spur-wheel G, substantially as shown and specified.

3. The arrangement of the gum/rollers M, on the brackets F, substantially as described.

In testimony that the above is my invention, I have hereunto set my hand and affixed my seal, this 25th day of May, 1869.

GEORGE P. FULLER. [L. S.]
